UNITED STATES PATENT OFFICE.

JOHN F. O'CONNOR, OF CHICAGO, ILLINOIS, ASSIGNOR TO WILLIAM H. MINER, OF CHICAGO, ILLINOIS.

EXECUTION DRAFT-RIGGING FOR RAILWAY-CARS.

1,130,323.

Specification of Letters Patent.

Patented Mar. 3, 1915.

Application filed March 14, 1913. Serial No. 754,223.

To all whom it may concern:

Be it known that I, JOHN F. O'CONNOR, a citizen of the United States, residing at Chicago, in the county of Cook and State of Illinois, have invented a certain new and useful Improvement in Friction Draft-Rigging for Railway-Cars, of which the following is a full, clear, concise, and exact description, reference being had to the accompanying drawings, forming a part of this specification.

My invention relates to improvements in friction draft rigging for railway cars.

The object of my invention is to provide a friction draft rigging for railway cars of simple construction and efficient operation.

In the drawings forming a part of this specification Figure 1 is a side elevation partly in longitudinal section on line 1—1 of Fig. 2 of friction draft rigging for railway cars embodying my invention. Fig. 2 is a plan view partly in horizontal section on line 2—2 of Fig. 1. Fig. 3 is an enlarged detail showing in perspective the friction shoes in assembled relation. Fig. 4 is a detail showing the inner side of one of the friction shoes. Fig. 5 is a detail of one of the antifriction rollers in perspective. Fig. 6 is an enlarged detail of the thimble in perspective. Fig. 7 is a cross-sectional view of the assembled friction shoes through the sets of the forward antifriction rollers.

In the drawings 8, 8 represent draft sills or parts of the car frame to which the draft rigging is attached, 9 a tie plate, 10 the end sill, 11 the buffer block, 12 the draw bar carry iron, 13 the draw bar, 14 the draft yoke, 15 the head thereof, transversely slotted for the reception of the coupler key 16, which passes through the said head and the draw bar, 17 the front follower, 18 the rear follower, 19, 19 the stop members, having the front stop shoulders 20, 20, rear stop shoulders 21, 21, front limiting stop shoulders 22, 22, and rear limiting stop shoulders 23, 23, 24 the draft gear mounted within the yoke, and comprising a hollow shell 25, preferably cylindrical in shape, and containing the friction mechanism 26 and spring mechanism 27.

The shell 25 is open at its forward end and closed at its rear end by the preferably integral plate 28. The friction mechanism comprises two sets of oppositely arranged

annular segmental friction shoes, a thimble 29 within said shoes, and a spring 30 seated between the two sets of shoes. The forward set 31 of friction shoes preferably comprises three in number, the rearward set 31^a being of the same number as the forward set. Each friction shoe 32 is of a general wedge shape, each having at either edge a pair of antifriction roller seats 33, 33. When in assembled position, as illustrated in Fig. 3 of the drawings, an antifriction roller seat 35 on each shoe is opposite an antifriction roller seat on an adjacent shoe, and between each of the thus oppositely arranged friction roller seats is disposed an antifriction roller 34.

While any suitable number of antifriction rollers may be employed between the friction shoes I prefer to employ two between each of the meeting edges of the oppositely arranged friction shoes.

Each friction shoe is provided at its edge with a shoulder 35, in preferable construction, back of which the roller seat 33 is formed.

Each shoe of the front set of friction shoes 31 is provided on its inner face with a shoulder 36, which when the said set is in assembled relation forms a seat for the outwardly extended flange 37 of the thimble 29 to engage against. Each shoe of the rear set 31^a of friction shoes is provided with a similar shoulder on its internal face, which when the shoes are in assembled position forms a seat for the inner spring 38, which said inner spring 38 is seated at its rear end 90 against the plate 28 of the shell 25.

The outer spring 39 is seated at its forward end against the rear set 31^a of friction shoes, and at its rear end against the plate 28 of the shell 25. Between the shoulders 95 upon the internal faces of the front and rear sets of friction shoes is seated the spring 30. A thimble 29 is forwardly provided with a recess 40 to receive the head 41 of the connecting rod 42, which passes through the said thimble and through the plate 28 at the rear end of the shell 25, where it is provided with a nut 43.

The outer friction faces 44 of both sets of friction shoes engage with the internal friction face 45 of the friction shell. The front follower 17 engages with the front set of friction shoes, and on rearward move-

ment of the draw bar the friction shoes of the front set and the friction shoes of the rear set are in wedging action against each other, the inward movement of the shoes being resisted by the spring mechanism 27. The shoes of each set spreads the shoes of the other set of friction shoes through pressure exerted by one set against the other set through the antifriction rolls 34, the said 10 pressure being applied to the edges of the said shoes. The spring 30 tends to keep the shoes of one set longitudinally separated from the shoes of the other set, and with the plurality of antifriction rolls assists in the 15 release action of the friction mechanism of the draft gear.

On forward movement of the draw bar the draft yoke moves the friction shell 25 forwardly, the parts within the shell being 20 compressed between the followers, the action

of said parts being similar in buffing movement of the gear.

I claim:—

In a draft gear in combination, a hollow cylinder, springs within the cylinder, 25 and friction mechanism within said cylinder, the friction mechanism including two sets of oppositely arranged annular segmental wedging friction shoes and antifriction rollers interposed between the adjacent 30 edges of said shoes, there being a plurality of rollers between each pair of adjacent edges and said rollers being arranged with their axes extending radially of the longitudinal axis of the cylinder.

JOHN F. O'CONNOR.
